CLAIM

The ornamental design for a portable electronic device case, as shown and described.

DESCRIPTION

FIG. 1 is a front perspective view of a portable electronic device case.

FIG. 2 is a rear perspective view of the portable electronic device case of FIG. 1.

FIG. 3 is a front view of the portable electronic device case of FIG. 1.

FIG. 4 is a left side view of the portable electronic device case of FIG. 1.

FIG. 5 is a right side view of the portable electronic device case of FIG. 1.

FIG. 6 is a rear view of the portable electronic device case of FIG. 1.

FIG. 7 is a top view of the portable electronic device case of FIG. 1; and,

FIG. 8 is a bottom view of the portable electronic device case of FIG. 1.

The broken lines depict portions of the portable electronic device case that form no part of the claimed design.
